US00D831359S

(12) **United States Design Patent** (10) **Patent No.:** **US D831,359 S**
(45) **Date of Patent:** **** Oct. 23, 2018**

(54) **TOOTHBRUSH**

- (71) Applicant: **Colgate-Palmolive Company**, New York, NY (US)
- (72) Inventors: **Eduardo Jimenez**, Manalapan, NJ (US); **Michael Rooney**, Millburn, NJ (US); **Robert Moskovich**, East Brunswick, NJ (US); **Andreas Wechsler**, Zell am See (AT); **Joachim Storz**, Zell am See (AT); **Raimund Klausegger**, Vienna (AT)
- (73) Assignee: **Colgate-Palmolive Company**, New York, NY (US)

(**) Term: **14 Years**

(21) Appl. No.: **29/443,323**

(22) Filed: **Jan. 16, 2013**

Related U.S. Application Data

CLAIM

The ornamental design for a toothbrush, as shown and described.

DESCRIPTION

FIG. 1 is a right front perspective view of a toothbrush according to the new design;
FIG. 2 is a left front perspective view thereof;
FIG. 3 is a right rear perspective view thereof;
FIG. 4 is a left rear perspective view thereof;
FIG. 5 is a front view thereof;
FIG. 6 is a rear view thereof;
FIG. 7 is a right side view thereof;
FIG. 8 is a left side view thereof;
FIG. 9 is a top view thereof, and,
FIG. 10 is a bottom view thereof.
The claimed design is formed of a translucent or transparent material. The portions of the toothbrush shown in broken lines form no part of the claimed design.

1 Claim, 5 Drawing Sheets
